UNITED STATES PATENT OFFICE.

JOSEPH L. CRAWFORD, OF RAYMOND, WASHINGTON.

RAZOR.

1,338,908.

Specification of Letters Patent.

Patented May 4, 1920.

Application filed August 14, 1918. Serial No. 249,838.

To all whom it may concern:

Be it known that I, JOSEPH L. CRAWFORD, a citizen of the United States, and a resident of Raymond, in the county of Pacific and State of Washington, have invented certain new and useful Improvements in Razors, of which the following is a specification.

This invention relates to razors, and an object of the invention is to provide a razor in which the cutting blade is interchangeable, and constructed in such manner that when the outer or toe end of the blade becomes dulled, the position of the blade may be reversed, for using the end of the blade which was previously at the heel end with respect to the handle, at the toe or outer free end of the blade holder.

A further object of this invention is to provide a razor blade holder or handle structure which is provided with a longitudinally extending groove to receive therein the back or blunt end of the blade and to magnetize the back structure of the holder for retaining the blade therein and which will permit the positioning of the blade at various projected positions with respect to the holder or handle structure.

A further object of the invention is to provide in a razor structure as specified, means, including a set screw for engagement with the blade and blade holder for use in connection with the magnetic attraction to hold the blade in position with respect to the holder and also to provide an abutment upon the holder provided with a recess in which the inner or heel end of the blade rests when the blade is properly positioned with respect to the holder or handle.

Other objects of the invention will appear in the following detailed description, taken in connection with the accompanying drawing, forming a part of this specification, and in which drawing:

Figure 1 is a perspective view of the improved razor.

Fig. 2 is a section on the line 2—2 of Fig. 1.

Fig. 3 is a fragmentary view partly in section of the razor blade and holder showing the set screw employed for preventing accidental movement of the blade.

Fig. 4 is a section on the line 4—4 of Fig. 1.

Fig. 5 is a side elevation of a modified form of blade.

Fig. 6 is a section through the holder showing the modified form of blade connected thereto.

Referring more particularly to the drawing, A indicates the usual handle of the razor, which has pivotally connected thereto the blade holder 1. The blade holder 1 is constructed of steel, and shaped similar to the shape of the back of an ordinary razor blade, it being adapted to be folded between the spaced sides of the handle A when not in use.

The holder 1, comprises the back portion 2 which is provided with a longitudinally extending recess extending upwardly from its lower edge. The recess 3, receives therein the blunt inner edge 4 of the razor blade 5 and the back 2 of the holder 1 is magnetized, to hold the blade 5 within the slot or recess 3 and prevent accidental movement thereof. The magnetizing of the back 2 of the holder 1, will cause the relatively thin lower edge portion of the back to cling snugly to the side surfaces of the blade 5, forming a fluid tight sanitary joint between the back 2 and the blade, preventing moisture, soap suds or the like from passing between the blade and the inner surfaces of the sides of the back of the holder. The blade 5 is shaped, so that when it is connected to the back 2 of the holder 1, these members will form a blade structure similar in shape to the ordinary razor blade and the point or cutting corners of the blade 5 may be either square or rounded as desired. The holder 1 is provided with an outwardly extending abutment 6. The abutment 6 is provided with a recess 7 formed therein in which the inner end of the blade 5 engages, forming a secure connection between the inner or heel end of the blade 5 and the body of the blade carrier 1 and also forming a support for the inner heel end of the blade.

If it is so desired, the blade 5 may be provided with cut-out portions 8 in each end thereof at its upper corner and these cut-out portions are provided to permit the connection between the threaded portion or shank of the set screw 9 with the threaded portion 100 of the inner surface of the back 2 of the holder 1. The head 10 of the set screw is of sufficient size to engage the end of the blade 5 as shown in Fig. 3 of the drawing, and it will therefore co-act with the magnetic contraction between the back 2 of the blade 5, in holding the blade securely in place with re-

spect to the holder 1 and preventing any accidental slipping movement of the blade, during use. The blade 5 is provided with the cut-out portions 8, one in each end, so that when the end of the blade which has been positioned at the outer end of the back 1 becomes dulled, the blade 5 may be reversed, positioning the end thereof which has previously been at the heel end of the holder, at the toe or outer free end of the same which permits prolonged use of the blade, as it is a well-known fact that the outer or toe end of a razor blade becomes dulled much quicker than the heel end thereof owing to the fact that it is more extensively used.

In Figs. 5 and 6 of the drawing, a modified form of the blade structure is shown. In this modified form, the blade 5^a is relatively flat, having its lower edge 5^b sharpened. The back 4^a of the blade 5^a has a clip 4^b, which is substantially U-shaped in cross section mounted thereon, which clip is shaped to snugly fit within the recess 3 in the back 2 of the holder. This clip 4^b, may either be permanently placed upon the blade 5, or it may be magnetized for holding it in proper position with respect to the blade 5^a when it is mounted thereon, and thereby per-

mitting it to be removed from the blade 5^a when the same has become dulled or otherwise rendered useless, for mounting upon a new blade 5^a and with this clip structure, supplied with the razor holder 1, either blades of the construction illustrated in Figs. 2 or 6 may be employed in connection with the holder.

Changes in details may be made without departing from the spirit of this invention; but

I claim:

In a razor, a blade holder provided with a longitudinally extending blade receiving recess terminating in a straight shoulder at its inner end, a blade of uniform width throughout its length and having a relatively thick back portion removably seated in said recess, said shoulder recessed to receive the inner end of the blade, said blade provided with cut-out portions at the upper corner of each end to permit the reversing of the position of the blade in the holder, a set screw threaded in the outer end of said holder and seating in said cut-out portion, the head of said set screw engaging the end of said blade to prevent accidental movement of the blade with respect to the holder.

JOSEPH L. CRAWFORD.
